UNITED STATES PATENT OFFICE

2,475,204

AUTOMOBILE WATER PUMP

Norval B. Simonson, Thermopolis, Wyo., assignor
of one-half to Oscar G. Simonson, Thermopolis, Wyo.

Application November 17, 1947, Serial No. 786,501

3 Claims. (Cl. 123—175)

1

This invention relates to improvements in automobile water pumps.

An object of the invention is to provide an improved non-leaking water circulating pump for circulating the water between the water jacket in the cylinder head of an automobile engine and the cooling radiator associated therewith.

Another object of the invention is to provide an improved form of circulating water pump of water cooled internal combustion engines which will have the bearing therefor removed from contact with the water being circulated.

A further object of the invention is to provide an improved automobile water pump which will be so constructed and arranged that the pump housing or casing may be readily removed without disturbing the fan belt which is used for driving the same, and said pump being supported upon the top of the engine cylinder head where it may be easily reached for making repairs or adjustments.

Another object of the invention is to provide an improved automobile water circulating pump which will be highly efficient in operation, and relatively inexpensive to manufacture and produce.

Other objects will appear as the description proceeds.

In the accompanying drawings which form a part of this application,

Figure 1 is a side elevation of an automobile engine and associated radiator, showing the improved water circulating pump supported upon the engine cylinder head;

Figure 2 is a top plan view looking down upon the improved water circulating pump showing the driving means therefor;

Figure 3 is a partial sectional view taken on the line 3—3 of Figure 1;

Figure 4 is a sectional view taken on the line 4—4 of Figure 2;

Figure 5 is a sectional view taken on the line 5—5 of Figure 4, and

Figure 6 is a sectional view taken on the line 6—6 of Figure 1.

Like characters of reference are used throughout the following specification and the accompanying drawings to designate corresponding parts.

In carrying out the invention, there is devised and provided an automobile engine 1 having a cylinder head 2 and a cooling radiator 3 associated therewith.

The cylinder head 2 is formed with a water outlet port or passage 4 through its upper wall,

2

and the annular base flange 5 of the improved water pump casing or housing 6 is bolted to the cylinder head 2 by means of the bolts 7 with the tubular pump casing 6 in vertical alignment with the water outlet port or passage 4.

An elbow pipe fitting 8 being internally threaded at its opposite ends 9 and 10 will be screwed upon the upper threaded end 11 of the tubular pump casing 6, and a vertical bearing 12 will be supported through the upper wall of the elbow fitting 8. The bearing 12 is provided with the packing 13 disposed in its upper end portion, being secured in place by the internally threaded bearing cap 14 threaded upon the externally threaded upper end 15 of the bearing 12.

An elongated screw impeller 16 provided with a central shaft 17 is rotatably disposed within the pump casing 6 with the upper end of the shaft 17 extending through the bearing 12, whose packing 13 is positioned above the water 18 in the pump casing 6 and elbow fitting 8, and is never contacted by the water as it is being circulated.

A spur gear 19 is secured upon the upper end of the shaft 17 and is adapted to mesh with a smaller spur gear 20 secured upon the upper end of the shaft 21 rotatably mounted between the upper bearing 22 and supporting bracket 23 attached by means of the bolt 24 to the elbow fitting 8, and a lower bearing 25 and supporting bracket 26 which will be attached to the horizontal bearing 27 supported by the bracket 28 upon the top of the cylinder head 2 by means of the bolt 29.

A bevel gear 30 is fixed upon the lower end of the vertical shaft 21 and meshes with a bevel gear 31 disposed upon the rear end of the shaft 32 supported in the horizontal bearing 27.

A pulley 33 is supported upon the front end of the shaft 32 and is driven by the fan belt 50 which extends about the pulley 34 upon the shaft 35 which supports the fan 36, and about the pulley 37 on the crank shaft 38 of the engine 1, being the driving means for the fan 36 as well as for the water pump impeller 16.

An outlet pipe 39 will be screwed into the threaded outer end 9 of the elbow fitting 8, and a hose connection 40 will be connected between the pipe 39 and the pipe 41 on the radiator 3, being secured in place by means of the hose clamps 42 and 43.

From the foregoing description, it will be apparent that there will be no leaking of the water pump possible, as the water line in the pump will be below the packing 13 in the bearing 12 for the

shaft 17 of the water impeller 16, and therefore the water 18 will never reach the packing 13.

The positioning of the water pump upon the top of the cylinder head 2 of the engine 1 provides for ready access to the same.

From the foregoing description, it will be apparent that there has been devised and provided a highly efficient form of automobile water circulating pump which will be relatively inexpensive to manufacture and produce.

While the preferred embodiment of the instant invention has been illustrated and described, it will be understood that it is not intended to limit the scope of the invention thereto, as many minor changes in detail of construction may be resorted to without departure from the spirit of the invention.

Having described the invention, what is claimed as new is:

1. A water circulating pump impeller comprising a vertically extended pump casing having a base attaching flange, an elbow on the upper end of said casing, a vertical bearing in said elbow, packing therefor above the water line in said elbow, a screw impeller disposed in said pump casing having a shaft formed thereon with its upper end disposed in said bearing, a spur gear on said shaft, a second shaft disposed in parallel relation to said pump casing, a spur gear on the upper end thereof in mesh with the spur gear on said impeller shaft, a horizontally mounted shaft adjacent said second shaft, meshed beveled gears on the rear end thereof and on the lower end of said second shaft, and a pulley on the front end of said horizontal shaft adapted to be driven by the usual automobile fan belt.

2. A water circulating pump impeller comprising a vertically extended pump casing having a base attaching flange, an elbow on the upper end of said casing, a vertical bearing in said elbow, packing therefor above the water line in said elbow, a screw impeller disposed in said pump casing having a shaft formed thereon with its upper end disposed in said bearing, a spur gear on said shaft, a second shaft disposed in parallel

relation to said pump casing, a spur gear on the upper end thereof in mesh with the spur gear on said impeller shaft, a horizontally mounted shaft adjacent said second shaft, meshed bevel gears on the rear end thereof and on the lower end of said second shaft, a pulley on the front end of said horizontal shaft adapted to be driven by the usual automobile fan belt, an outlet pipe connected with said elbow, and a hose connection connected therewith and to the usual automobile cooling radiator.

3. In combination with an automobile engine having a cylinder head and a cooling radiator associated therewith, a vertically extending pump casing having a base attaching flange supported upon said cylinder head, said cylinder head being formed with a vertically aligned outlet passage in vertical alignment with said pump casing, an elbow on the upper end of said casing, a vertical bearing in said elbow, packing therefor above the water line in said elbow, a screw impeller disposed in said pump casing having its lower end extending through the bottom thereof and a shaft on its upper end extending through said bearing and means for connecting said elbow with the usual automobile cooling radiator, and means for driving said impeller.

NORVAL B. SIMONSON.
